UNITED STATES PATENT OFFICE.

WILLIAM H. ESCHBACH, OF WABASH, INDIANA.

DETACHABLE HINGE.

No. 920,936.

Specification of Letters Patent. Patented May 11, 1909.

Application filed October 27, 1908. Serial No. 459,772.

To all whom it may concern:

Be it known that I, WILLIAM H. ESCHBACH, a citizen of the United States, residing at Wabash, in the county of Wabash and State of Indiana, have invented certain new and useful Improvements in Detachable Hinges; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to detachable hinges, and has for its object to provide a device of this class which is particularly simple in its construction, easy and cheap to manufacture, and employing a minimum amount of material.

A further object of my invention is to provide a detachable hinge, the leaves of which are stamped out of sheet metal requiring no casting.

A further object of my invention is to provide a detachable hinge stamped out of sheet metal and so constructed as to provide an extremely long and durable bearing.

With these objects in view my invention consists in the novel construction of one leaf of the hinge and the stationary bracket to which the hinge leaf co-operates.

Referring to the accompanying drawing: Figure 1 is an elevation of the detachable hinge constructed in accordance with my invention. Fig. 2 is an elevation of the bracket. Fig. 3 is a vertical sectional view through the hinge and bracket taken on line 3-3 of Fig. 1. Fig. 4 is a transverse sectional view taken on line 4-4 of Fig. 1, and Fig. 5 is an edge view of the hinge.

Like numerals of reference indicate the same parts throughout the several figures in which:

1 indicates the hinge which comprises the leaves 2 and 3. The leaf 3 may be of any design but preferably as shown in Fig. 1, and is stamped out of sheet metal being provided with suitable perforations to receive screws. 4: The leaf 2, as shown in Fig. 1, is provided with a tongue or extension 5, which tongue or extension extends from the point 6 which is on a line with the bottom edge 7 of the leaf 3 and passes parallel with the axis 5 of the hinge to the point 8.

9 indicates the bracket which is stamped

out of sheet metal and provided with suitable perforations 10 to receive screws for fastening the same rigidly in position, said bracket 9 being provided with a slot 11, each edge of said slot being provided with a retaining flange 12, said retaining flanges 12 being formed to receive the tongue or extension 5 of the hinge leaf 2 as clearly shown in Fig. 1.

As will appear from Fig. 1 the extension or tongue 5 is somewhat longer than the slot 11 so that when said tongue or extension 5 is in position within the retaining flanges 12 the extreme lower end 13 of said tongue or extension extends below the extreme lower end 14 of the slot 11 engaging the flat surface 15 of the supporting bracket 9.

Referring again to Fig. 1 it will be seen that shoulders 16 and 17 are formed on the hinge leaf 2 on each side of the tongue or extension 5, said shoulders 16 and 17 engaging the upper ends 18 of the retaining flanges 12 as clearly shown in Fig. 1, thus limiting the entrance of the extension or tongue 5 within the retaining flanges 12 and forming a strong rigid and durable stop.

As will appear from the drawing, the extension or tongue 5 within the retaining flanges 12 of the supporting bracket 9 are below the hinge proper; this construction allowing the device to be no wider than an ordinary hinge, while at the same time it allows an exceptionally long rigid bearing for the device, greatly strengthening and increasing the life of the same. By reason of this construction it is also apparent that the entire device can be stamped out of sheet metal, thus reducing the cost of production and obviating the necessity of casting.

Having thus fully described my invention what I claim as new and desire to secure by Letters Patent of the United States is:

1. A detachable hinge comprising two hinge leaves and a supporting bracket, one of said hinge leaves being provided with a tongue or extension formed below the lower edge of the hinge leaves and extending downwardly in a line parallel with the axis of the hinge, said supporting bracket being provided with a vertical slot and a retaining flange on each side of said slot to receive the said tongue or extension, the said tongue or extension being longer than the said retaining flanges and slot in such manner that the end of said tongue or extension engages the flat surface of the retaining bracket, shoul-

ders formed on each side of said tongue or extension to engage the upper ends of the said retaining flanges to limit the entrance of the said tongue or extension within the said retaining flanges.

2. A detachable hinge comprising two hinge leaf sections, a tongue or extension formed on one of said leaves and extending downwardly therefrom in a line parallel with the axis of the hinge and supporting bracket, said supporting bracket comprising two re-

taining flanges to receive the said tongue or extension on one of the hinge leaves, said tongue or extension and the said retaining flanges being below the lower edge of the hinge leaves proper.

In testimony whereof I affix my signature, in presence of two witnesses,

WILLIAM H. ESCHBACH.
